UNITED STATES PATENT OFFICE.

RUDOLPH HOFFMAN, OF LORAIN, OHIO, ASSIGNOR TO AMERICAN STOVE COMPANY, OF ST. LOUIS, MISSOURI, A CORPORATION OF NEW JERSEY.

GAS-STOVE-DOOR LATCH.

No. 927,240.

Specification of Letters Patent.

Patented July 6, 1909.

Application filed January 25, 1909. Serial No. 474,119.

To all whom it may concern:

Be it known that I, RUDOLPH HOFFMAN, a citizen of the United States, residing at Lorain, in the county of Lorain and State of Ohio, have invented certain new and useful Improvements in Gas-Stove-Door Latches, of which the following is a specification, reference being had therein to the accompanying drawing.

10 This invention relates to improvements in gas stove door latches, and the object of the invention is to provide a handle-operated latch so constructed, that in the event of an explosion because of gas accumulation in 15 the stove before lighting, the latches of the doors will yield and permit the door or doors to open, thus preventing injury to the stove.

In the accompanying drawings, Figure 1, is a perspective view of a portion of a gas 20 stove showing the improved latch applied to the doors thereof. Fig. 2, is a sectional view of the improved latch showing it in the closed position. Fig. 3, is a sectional view showing the latch in its yielding position to permit the opening of the door under 25 the force of an explosion within the stove. Fig. 4, is a sectional view of a modified form of the improved latch. Fig. 5, is a sectional view on the line 5—5 of Fig. 4.

30 It is well known to those skilled in this art that if in the operation of the stove the gas of the main burner or burners is turned on, an accumulation of gas in the stove occurs, and if then lighted there is liable to be an 35 explosion, which sometimes damages the stove.

This invention is designed to permit the automatic opening of the door or doors of the stove in the case of an explosion therein, 40 thus releasing the expansive force of the explosion and preventing injury to the stove.

The present improvement, as embodied in the form of latches shown in Figs. 1, 2 and 3, comprises a latch handle 1 which is secured 45 to an oscillating latch-stem 2 which passes through the stove door 3 and carries at its inner end a latch 4. This latch 4 is pivoted to the stem 2 at the point 5, and surrounding the stem 2 is a suitable sleeve 6. The inner 50 face of this sleeve 6 engages the adjacent face of the pivoted latch 4, while the opposite or outer face of the sleeve 6 is engaged by a spiral spring 7, the said spring 7 having its opposite end resting against a flange 8 which

is part of a hollow boss 9 which projects from 55 the door 3. The spring and sleeve are located within this boss, and a flange 10 connected to the latch stem 2 engages the outer end of the boss 9, the spring thus serving to hold the parts in position and permitting the 60 sleeve 6 to be depressed by the swinging of the latch 4, as shown in Fig. 3, to automatically release the door. Preferably, the end 11 of the latch is tapered or curved as shown at 65 12 to permit the locking end of the latch to more freely swing into the position shown in Fig. 3. The locking end of the latch 4 is adapted to engage the door frame 13 which acts as a latch keeper for locking the door closed. When it is desired to release the 70 door the stem 2 is oscillated by means of the handle 1 to turn the locking end of the latch out of engagement with the door frame 13, and the door is locked in a closed position by 75 turning the handle to carry the locking end of the latch in engagement with the door frame 13 after the door is closed. From this description it will be seen that the latch is a handle-operated one for locking the door closed, and for releasing the door to permit 80 it to be opened, but will automatically yield and permit the door to be opened under the expansive pressure of an explosion within the stove.

In Figs. 4 and 5, a modified form of this 85 invention is shown, in which instance the handle 14 is secured to a suitable casting 15, the ends 16 of this casting being of rocker form and resting in correspondingly-shaped 90 depressions 17 which are formed in the door 18. Projecting through the door 18 from the casting 15, and preferably at its center, is an arm 19, and this arm also passes through a suitable flat form spring 20, the 95 spring having its ends 21 resting against the inner side of the door 18, and bowed outward between its ends, as clearly shown in Fig. 4. A latch 22 is pivoted to the inner end of the arm 19 and the latch rests against the spring 20. The spring thus serves to hold the handle in an extended position and also permits the latch to turn on its pivot 23 to automatically release the door in the case of an 100 explosion for the purposes previously stated. The spring also serves to hold the latch in the locking position shown in solid lines, Fig. 5, but the latch can be thrown to the unlocking position shown in dotted lines, Fig. 5, by 105

moving the handle 14 laterally, thus rocking it on its rockers 16. This modified form is also a handle-operated latch for locking the door closed, and permitting it to be opened, 5 while at the same time it will automatically release the door and permit it to be opened should an explosion occur within the stove.

I do not limit myself to the specific constructions herein shown, the primary feature 10 of the invention being a handle-operated latch which is movable to a releasing position automatically by reason of outward pressure on the door.

Having thus described my invention, what 15 I claim and desire to secure by Letters Patent, is:—

1. The combination with a gas stove door and door frame, of a latch carried by the door and adapted to engage with the door 20 frame and to be operated by the opening movement of the door, and a handle operatively connected with the latch to move it independent of the door frame.

2. The combination with a gas stove door 25 and door frame, of a pressure operated latch carried by one of said members and engaging the other of said members, and a latch operating handle operatively connected with the latch.

3. The combination with a gas stove door and latch keeper, of a latch engaging the keeper to hold the door closed, one of said 30 members movable to unlocking position under outward pressure for the purpose described, and a latch operating handle connected with the latch to move it independent of said outward pressure.

4. A latch for gas stoves comprising a door, a handle operated member carried by 40 the door, a latch keeper, a latch pivoted to the said handle operated member and engaging the keeper, a spring for holding the latch in locking position but permitting it to yield to unlocking position under outward 45 pressure upon the door independent of the

handle operated member, the parts operating for the purpose described.

5. A latch for gas stove doors comprising a movable handle operated member, a latch pivoted to said member and movable therewith to locking and releasing position, and a spring adapted to hold the latch in its locked 50 position but permitting the latch to yield to an unlocking position under outward pressure upon the door.

6. A latch for gas stove doors, comprising a handle operated member, a latch keeper, a latch pivoted to the handle member and movable in a direction at right angles to the movement of said member by outward pressure 60 engagement with the keeper, a spring for normally holding the said latch against said movement, whereby the latch may be moved by the handle operated member to locking and releasing position, and moved to 65 a releasing position by outward pressure independent of the said handle member.

7. A latch for gas stove doors, comprising a handle operated member, a latch keeper, a latch pivoted at right angles to the said 70 member and projecting to opposite sides of its pivotal point, a spring exerting pressure upon the latch at opposite sides of its pivotal point, the latch thereby adapted to be moved to locking and releasing positions by the 75 handle member, and to releasing position against the tension of the spring by outward pressure engagement with the keeper independent of the handle member.

8. The combination with a gas stove door 80 and latch keeper, of a pressure operated latch carried by the door and engaging the keeper, and an oscillating handle operating the latch independent of said pressure.

In testimony whereof I affix my signature 85 in presence of two witnesses.

RUDOLPH HOFFMAN.
